UNITED STATES PATENT OFFICE.

HENRY DEITCHLER, OF MINNEOLA, IOWA.

COMBINED CULTIVATOR AND HARROW.

SPECIFICATION forming part of Letters Patent No. 368,935, dated August 30, 1887.

Application filed June 20, 1887. Serial No. 241,912. (No model.)

To all whom it may concern:

Be it known that I, HENRY DEITCHLER, a citizen of the United States, residing at Minneola, in the county of Mills and State of Iowa, have invented a new and useful Corn Cultivator and Harrow Combined, of which the following is a specification.

My invention relates particularly to improvements in cultivators for listed corn, combined with a harrow for general work.

The objects of my invention are to accomplish in a better manner than heretofore several different kinds of farm labor with a single implement. I attain these objects by the mechanism illustrated in the accompanying drawings, in which—

Figure 1 is a perspective view of one of the sections or halves of the machine disconnected and showing but one of the fender-boards A. Fig. 2 is a perspective view of the other section or half of the machine, also detached, and showing but one of the fender-boards A, but showing the section or half set or adjusted to fit the ridges between the rows of listed corn by means of the gage or clamp B B C. Fig. 3 is a view of the two sections or parts of the machine attached together by means of the rod D and the gages or clamps B B C, set so that the two parts of each section are kept rigid with reference to each other, and showing the handles E and cultivator-shovels and beams F removed, and also showing a chain, f, attached to hitch to for harrowing purposes. Fig. 4 is a side view of one of the fender-boards A detached, showing the slotted adjustable lugs a and the slotted adjustable brake or gage b. Fig. 5 is a top view of the two slotted adjustable parts of the brace G detached and disconnected, showing the slots c. Fig. 6 is a vertical section of one of the standards or supports, B, of the section-gage B B C, and showing the bolt-holes d e. Fig. 7 is a side view of the cultivator-beam F and shovel detached. Fig. 8 is a perspective of the clamp or collar H, which attaches the beam F to the cross-bar of the gage C, showing the plate g attached by nuts running on threads cut on the ends of the clamp H.

Similar letters refer to similar parts throughout the several views.

My machine consists, essentially, of bars of iron or other metal, I, having the ends bent downward and (with reference to each half-section) also bent outward to form lugs or arms J, in which I make bolt-holes h. Near the ends of said bars I, I also make bolt-holes i. Through these I bolt to I other similar bars, K. Through the bars K, I make other holes, k, adapted to receive harrow-teeth secured therein in any convenient manner. I also attach to the bars I and K a brace, G, composed of similar material, but consisting of two slotted parts, as shown in Fig. 5. This slotted bar G is bolted by the same bolt at i 65 to I and K at the outer front corners and the inner back corners of the several half sections, as shown in Figs. 1 and 2.

Near the back end of the brace G, and in each part thereof, I make a narrow slot, c, 70 adapted to receive a bolt, l, by means of which the two parts of the brace G can be adjusted and fastened together, thus permitting the width of the machine to be accurately adjusted to corn-rows of varying width.

In the cross-bars K, at the front ends of the several half-sections, I insert teeth in the holes k. These teeth may be of any desired form; but I prefer common harrow-teeth, with the upper end shouldered, and a thread and nut on 80 the end so arranged as to give the teeth a little slant backward. I also put similar teeth in the brace G for perhaps three-fourths of its length from the front end. Near the back end of G, I omit the teeth to permit the escape of 85 any clods or lumps which may pass through the teeth of K, and which may also fail to be pulverized by being forced up the sides of the ridge, and thus prevent all possibility of the machine becoming clogged. The curved arms 90 J, with holes h, admit of the half-sections being attached together by means of a rod, D, with nut or key at one end and an eye at the other, or they may be attached by bolts and nuts through the bolt-holes h.

The team may be attached to the eye in D or to a chain or other fastening passed round the arms J. I attach one horse to each section with a singletree, using no doubletree, but having the team otherwise harnessed together 100 as usual, and each horse walks on a ridge between rows, while the driver guides the ma-

chine by means of the handles E, one of which is attached to each section. The handles are common wooden ones bolted to an iron plate or piece, m, so arranged as to admit of its being bolted to the bars I through suitable holes made for the purpose. To the handles I also attach light iron braces L, suitably bent and provided with holes, bolted together at the upper ends through the handles and held at the lower ends by the same bolts, i, which connect the bars I and K. By varying the angles of the braces L the handles can be set in any desired position, and the inner brace L may be suitably bent and fastened at its lower end by 15 the bolt or rod passing through the arms J. Both the handles can be thus attached to a single section when it is desired to harrow in grass-seed or grain in standing cornstalks. In the latter case the cultivator-beams and shovels 20 F are removed and the second handle bolted on through the beam-lug bolt-holes n.

On the bar I of the inner part of each section I attach a metal lug or arm, o, by a bolt passing through both, adapted to be bolted to the beam at its lower end through the bolt-hole n. To this lug I attach the bent and curved metal beam F, adapted to pass over the cross-bar C and carry at a suitable depth a common cultivator-shovel, which cuts down the apex 30 of the ridge. The beam F is secured to the cross-bar C by means of the clamp H, which insures that the beam shall always ride perpendicularly, it being capable of rotation on the bolt n. Near the rear ends of the two inner bars, I, of each section I attach metal standards B, made of bar-iron sufficiently heavy to support the two bars I, to which they are attached, and maintain the two sections in the 35 shape of an obtuse letter V inverted, as shown in Fig. 2, by means of bolts d, passing through the feet of the standards and the bars I, fastening them rigidly together.

The slot or opening in the standards B, I make adapted to receive a cross-bar, C, and 45 through them I make holes e, with corresponding holes in the cross-bar C, so made as to admit of bolts fastening the tops of the standards at any desired distance apart, while the two sections turn to the necessary extent upon the 50 rod D, or bolts in lieu thereof. I thus make the bars K ride parallel with the sides of the ridge, whatever be their angle. I then adjust the bars I, which are carried next to the rows of corn, to the proper distance by means of the 55 slotted brace G. To the lugs or arms J, which pass next to the rows of corn, I attach a fender-board, A, sufficiently wide and long to prevent the corn being buried. To this I bolt 60 slotted reverse lugs a, to permit the board to be adjusted as to height, and also to enter the holes

in J. To hold the fender-board in position I attach a slotted gage, b, which is merely a piece of bar-iron bent at right angles with the slotted portion thereof. The bent part of b strikes upon the bar I and maintains the board in any 65 desired position.

The different parts may be made of any desired size, but for all ordinary purposes the bars I K and beam F may be of common bar-iron one and one-half or one and three-eighths inch by 70 one-half or three-eighths of an inch. I make the bars I about three feet long and K about one and one-half foot long. I make it all of iron or other metal, except the handles and fender-boards. It is used as a cultivator, like the ordinary one, 75 except that the horses are attached as if to a tongueless cultivator and the handles are manipulated in the rear. By pressing upon them the machine can be made to spread the dirt so as to cover the entire surface between the 80 rows when they widen, and by raising the handles slightly the area of work can be considerably narrowed if irregular rows require. Thus by adjusting it properly and manipulating it carefully the entire surface of a corn-field can be thoroughly cultivated and cleaned, 85 as it cleans two rows at once. When used as a harrow, I remove the beam F, the handles E, set the gages B B C so that the sections are all in the same plane and work on the rod D as 90 a pinion, and attach a chain, f, or other means of hitching thereto in such a manner that it will be drawn at an angle, when the teeth will cover the whole surface. When used as a single harrow, I remove the shovel-beam F, attach the other handle in place of the beam, (and its braces L,) adjust the braces G, and 95 use one horse.

I am aware that combined cultivators and harrow with gage attachments have been 100 used, and I do not, therefore, claim such a combination, broadly; but

What I do claim, and desire to secure by Letters Patent as my invention, is—

1. In a combined harrow and cultivator, the 105 side bars, I, harrow-bars K, and sectional braces G, in combination with the clamp or gage B B C, perforated ears J, rod D, lugs n o, shovel-beams F, clamp H, and handles E, substantially as shown and described.
2. The combination of the harrow-frame I K G, connecting-rod D, hinged feeder A, with stop or gage b, gage-clamp B B C, shovel-beam F, clamp H, and handles, substantially as shown and described.

HENRY DEITCHLER.
